IRONING TABLE

Oscar A. Flagstad, Minneapolis, Minn.

Original application February 13, 1935, Serial No. 6,300. Divided and this application September 8, 1936, Serial No. 99,728.

11 Claims. (Cl. 38—119)

This invention relates to ironing tables of the collapsible type and the primary object is to provide a comparatively simple, efficient, and practical construction of table that is virtually automatic in folding and setting up operation, by which is meant that it is entirely unnecessary for the operator to do more than pick the table up and tilt it to effect the collapsing operation or to return it to normal horizontal position to 10 completely restore the supporting legs and braces to operative position.

A further object is to provide a new and novel design of spreadable rear leg frame, which is also automatically operative, when the table is set 15 up and collapsed, and which has for its object to transversely spread the rear leg frame, to thereby give better lateral support when the table is in use, and which will contract or close such legs toward each other, when the table is 20 collapsed, so as to narrow the width of the structure and thereby economize on space when packing, shipping, and storing the table.

In addition to the foregoing and highly important aspect of the invention, it may additionally be noted that the table is so formed as to 25 utilize a minimum amount of material and is therefore light in weight and economical of manufacture, and, further, is so formed that when in use it is unusually sturdy and rigid, a 30 primary consideration in all ironing tables.

The present application is a division of my 35 pending application Serial No. 6,300, filed February 13th, 1935, for Ironing table, which application has matured into Patent No. 2,056,004, on September 29th, 1936, and attention is directed to that patent for further understanding of the present structure as well as the broader conception of the invention in its more general aspects.

In the accompanying drawings, which illustrate 40 a preferred embodiment of the invention:

Fig. 1 is a side elevation of the table as set up and ready for use.

Fig. 2 is a side elevation of the table as shown 45 in Fig. 1, but showing it in a partly lifted, tilted and collapsed condition.

Fig. 3 is an enlarged detail section on line 3—3 in Fig. 2.

Fig. 4 is a rear elevation of the table when set 50 up for use, or as seen from the left in Fig. 1.

Fig. 5 is a rear elevation of the table when in its vertical and completely collapsed condition.

Fig. 6 is an enlarged, detail sectional elevation 55 on line 6—6 in Fig. 4, but with certain parts broken away.

Fig. 7 is an enlarged, detail section on line 7—7 in Fig. 4.

Reference will now be made to the various figures of the drawings by reference characters, like parts being designated by like characters in 5 the particular figures wherein such parts are shown. It may here be noted that as a matter of convenience the terms "board" or "ironing board" will be used in its popular sense to indicate broadly the flat element presenting the ironing 10 surface, and regardless as to whether said "board" is strictly a wooden board, or is made of sheet metal or other material; and, the terms "table" or "ironing table" will be employed in the broad sense of including both the "board" 15 and also the supporting structure which is made up of the legs, braces, and other collapsible elements.

The table essentially comprises an ironing board A, a rear supporting leg frame B, a forward or front leg frame C, a connector frame D, connecting the leg frames, and a brace frame E which constitutes a truss between the rear end 20 of the board A and leg frame B.

The two leg frames B and C are pivotally attached at their upper ends, as at 8, to depending lugs 9 of a cross bar 10 secured to the underside of the board A. The rear leg frame comprises upper and lower sections 11 and 12, respectively, pivotally connected as at 13, and with the lower 30 section extending above the pivot for stopping engagement against the upper section so as to produce a jack knife joint effect maintaining the sections in alignment when the frame is in erected position, as shown in Figs. 1 and 4.

The frame section 11 includes two laterally disposed links connected by a transverse bar 14, which bar has right angular lugs at its ends, pivoted to the links of the section 11, as at 15. The legs proper of the frame section 12 are shown as 40 being formed of angle iron, and these legs are connected by a pair of toggle links 16, joined by pivot pin 17. This pin also serves as a pivot connection for the lower end of a connecting or tie rod 18, the upper end of which attaches centrally to the cross bar 14 as at 19.

The leg frame C is generally V-shaped in form and is preferably made of a single solid rod bent at its middle to form the two side members. This leg frame of course provides the third point of 50 floor support for the table, and to maintain proper spacing and rigidity is tied to the legs of frame B by the connector frame D which is also V-shaped in form and preferably formed of bar or rod iron. The connection between the apex ends 55

- of frames C and D must provide relative pivoting action and preferably comprises an eye forming strap 24 of one frame encircling the other. The rear ends of the bars forming frame D are pivotally connected to the frame B by being formed with loops or eyes 20 (Fig. 3), through which extend extensions 21 of the frame E, these extensions being riveted to the frame legs 12, as at 22, after passing through spacer collars 23.
- 10 The brace frame E is also generally V-shaped in form, to better brace the rear end of the board with respect to the other frames, and is pivotally secured at its upper end to the board by a hinge forming bracket 25.
- 15 The operation of the table may be explained as follows: When the table is in its vertical and collapsed position, as shown in Fig. 5, the various parts will assume the positions as therein shown, and at which time, as previously noted, 20 the legs 12 will be drawn in so as not to project beyond the lateral limits of the board. This drawing in is effected by the connecting rod 18 which breaks the joint between the links 16, and by a toggle action moves them downwardly to 25 thereby pull in the legs 12. It may here be noted that the pivotal connections 8 and 13 have a slight amount of freedom to permit this transverse swinging action of the legs. When the table is to be set up the board A is merely grasped and 30 gradually lowered to its horizontal position, and as this movement is effected the various frame and supporting parts move through the position indicated in Fig. 2 and to the final position as shown in Figs. 1, 4, and 6, the action of gravity 35 being the only force required to move the parts into their respective places; and if the leg sections 11 and 12 do not immediately assume their aligned positions they will immediately do so upon slight pressure being exerted downwardly on the 40 board A.
- It is of course understood that as the rear leg frame assumes its operative position the connecting rod 18 will pull up on the toggle links 16 until they are drawn into horizontal positions as 45 indicated in Figs. 4 and 7, and at which time the lower ends of the legs 12 are forced outwardly to their spread positions.
- When the table is to be collapsed after use, the operation is reversed, and ordinarily the parts 50 will, without any special assistance, function as desired. However, if the joint 13 does not immediately break because of friction, as might be caused by paint or too tight pivot points, then the operator only has to exert a slight rearward pressure on this joint after the table has first been 55 slightly lifted off of the floor; and when this is done the respective movements of the several parts will automatically function as indicated.
- It may here be noted that inasmuch as the 60 connector frame D does not slide with respect to the frame B, it is necessary to provide the joint 13 in the rear leg frame so that when the sections 11 and 12 are jack-knifed or doubled against themselves, the distance between the centers 24 and 21 and thence to 13 will be equal to the distance from the point 24 through the pivot 8 and to point 13. And the joint 13 must be so located that when the various frames are entirely collapsed the distance from the center 21 to the 65 center 13 will be equal to the length of the links 11, plus the distance from the center 21 to the pivot 8. The purpose of the pivots 15 is to permit the cross bar 14 to turn on the axes of these pivots so that the connecting rod 18 can be rigidly secured against one of the flat faces of the cross 70

bar 14, the turning movement at 15 being required by the folding action as indicated in Fig. 2. When the connecting rod 18 has pulled the toggle links 16 up into the horizontal positions indicated in Fig. 4, it will of course be obvious that these links will cooperate to form a rigid connection between the legs inasmuch as the connecting pivot pin 17 is then retained by the rod 18 at a fixed elevation.

It is understood that suitable modifications 10 may be made in the structure as disclosed, provided such modifications come within the spirit and scope of the appended claims. Having now therefore fully illustrated and described my invention, what I claim to be new and desire to 15 protect by Letters Patent is:

1. A collapsible ironing table comprising a normally horizontal board, downwardly diverging front and rear leg frames pivotally connected at their upper ends to the board intermediate its 20 ends, the rear leg frame having a jack knife joint intermediate its upper and lower ends for breaking movement from the normal erected position of the frame, a member connecting the leg frames to maintain them in normal board supporting positions, and a brace frame connecting the rear end of the board to the rear leg frame to maintain the board in its horizontal position.

2. A collapsible ironing table comprising a normally horizontal board, downwardly diverging front and rear leg frames pivotally connected at their upper ends to the board intermediate its ends, means connecting the leg frames to prevent them from spreading beyond erected positions, and an inclined brace frame having pivot connections at its opposite ends with the board and rear leg frame, respectively, to support the board in operative position, said rear leg frame being collapsible above the point of its pivot connection with the brace frame to permit collapsing 40 of the several frames into parallel positions adjacent the board.

3. A collapsible ironing table comprising a normally horizontal board, downwardly diverging front and rear leg frames pivotally connected at their upper ends to the board intermediate its ends, means connecting the leg frames to prevent them from spreading beyond erected positions, and an inclined brace frame having pivot connections at its opposite ends with the board and rear leg frame, respectively, to support the board in operative position, said rear leg frame being sectionally formed above the point of its pivot connection with the brace frame, and said sections having interbracing contact with each other 55 when in erected positions, thereby to form a rigid support for the rear end portions of the board.

4. A collapsible ironing table comprising a normally horizontal board, downwardly diverging front and rear leg frames pivotally connected at their upper ends to the board intermediate its ends, the rear leg frame having a jack knife joint intermediate its upper and lower ends for breaking movement from the normal erected position of the frame, a connector frame secured 60 at one end to the front leg frame, and pivotally attached at its rear end to the rear leg frame, and a brace frame having fixed pivot connections at its opposite ends with the board and rear leg frame respectively.

5. A collapsible ironing table comprising a normally horizontal board, downwardly diverging front and rear leg frames pivotally connected at their upper ends to the board intermediate its ends, the rear leg frame having a jack knife 70

- joint intermediate its upper and lower ends for breaking movement from the normal erected position of the frame, a connector frame secured at one end to the front leg frame, and pivotally attached at its rear end to the rear leg frame, and a brace frame having fixed pivot connections at its opposite ends with the board and rear leg frame respectively, said front leg frame and connector frame both being substantially V-shaped in form and having their apex ends pivotally connected, and said rear leg frame having transversely spaced members for contact with the floor and providing lateral support for the board.
6. A collapsible ironing table comprising a normally horizontal board, downwardly diverging front and rear leg frames pivotally connected at their upper ends to the board intermediate its ends, the rear leg frame having a jack knife joint intermediate its upper and lower ends for breaking movement from the normal erected position of the frame, a connector frame secured at one end to the front leg frame, and pivotally attached at its rear end to the rear leg frame, and a substantially V-shaped, inclined brace frame secured 25 with its apex end to the rear end of the board and its arms pivotally attached to the sides of the rear leg frame.
7. An ironing table comprising a board pivotally secured intermediate its ends to a rearwardly inclined rear leg frame and a forwardly inclined front leg frame, a leg spacing frame rigid throughout its length and having fixed pivot connections at its front and rear ends with the respective front and rear leg frames, said 30 rear leg frame having a transverse joint intermediate its pivot connections with the board and spacing frame permitting a jack knife folding action of the upper part of the rear leg frame, and a brace frame connecting the rear leg frame to the rear end of the board.
8. An ironing table comprising a board pivotally secured intermediate its ends to a rearwardly inclined rear leg frame and a forwardly inclined front leg frame, a leg spacing frame rigid throughout its length and having fixed pivot 45 connections at its front and rear ends with the respective front and rear leg frames, said rear leg frame having a transverse joint intermediate its pivot connections with the board and spacing frame permitting a jack knife folding action of the upper part of the rear leg frame, and a brace frame connecting the rear leg frame to the rear end of the board, said brace frame being rigid

lengthwise to support both ends of the board against tilting movement on the leg frames when in erected positions.

9. An ironing table comprising a board pivotally secured intermediate its ends to a rearwardly inclined rear leg frame and a forwardly inclined front leg frame, a leg spacing frame rigid throughout its length and having fixed pivot connections at its front and rear ends with the respective front and rear leg frames, said rear leg frame having a transverse joint intermediate its pivot connections with the board and spacing frame permitting a jack knife folding action of the upper part of the rear leg frame, and a brace frame connecting the rear leg frame to the rear end of the board, said brace frame having pivot forming ends connecting the spacing frame to the rear leg frame.

10. An ironing table comprising a board pivotally secured intermediate its ends to a rearwardly inclined rear leg frame and a forwardly inclined front leg frame, a leg spacing frame rigid throughout its length and having fixed pivot connections at its front and rear ends with the respective front and rear leg frames, said rear leg frame having a transverse joint intermediate its pivot connections with the board and spacing frame permitting a jack knife folding action of the upper part of the rear leg frame, and a brace frame connecting the rear leg frame to the rear end of the board, said rear leg frame having transversely spreadable legs, and means responsive to the straightening and folding of the rear leg frame for spreading and contracting the legs with respect to each other.

11. An ironing table comprising a board, downwardly diverging front and rear leg frames pivotally attached to and for supporting the board, means for releasably bracing the leg frames and board in erected positions, said rear leg frame having upper and lower sections pivotally joined below the point of pivot attachment to the board, said lower section having transversely spreadable legs, and means operative upon swinging said leg sections with respect to each other and on their connecting joint to spread and close the legs with respect to each other, said last mentioned means comprising a pair of toggle links connecting said legs of the lower section, a bar connecting the upper sections of the legs, and a rod connecting the links to the bar.

OSCAR A. FLAGSTAD.
